(57) **CLAIM**

The ornamental design for a female electrical connector, as shown and described.

DESCRIPTION

FIG. 1 is a top, front, left side perspective view of my new design for a female electrical connector.

FIG. 2 is a front side elevational view thereof.

FIG. 3 is a top plan view thereof.

FIG. 4 is a bottom plan view thereof.

FIG. 5 is a right side elevational view thereof, the left side elevational view being identical thereto; and,

FIG. 6 is a rear side elevational view thereof.

The broken lines in FIGS. 2 and 5 are included to show environmental structure and form no part of the claimed design.
